UNITED STATES PATENT OFFICE.

CHESTER McNEIL, OF CHICAGO, ILLINOIS, ASSIGNOR TO UNION SPECIAL MACHINE COMPANY, OF CHICAGO, ILLINOIS, A CORPORATION OF ILLINOIS.

THROAT-PLATE FOR SEWING-MACHINES.

1,266,837.

Specification of Letters Patent. Patented May 21, 1918.

Application filed July 20, 1915. Serial No. 40,885.

To all whom it may concern:

Be it known that I, CHESTER McNEIL, a citizen of the United States, residing at Chicago, in the county of Cook, State of Illinois, have invented certain new and useful Improvements in Throat-Plates for Sewing-Machines, of which the following is a description, reference being had to the accompanying drawing and to the figures of reference marked thereon.

The invention relates to new and useful improvements in throat plates for sewing machines and more particularly to a throat plate which is adapted to be used in connection with a stitching mechanism for forming a flat seam.

An object of the invention is to provide a throat plate having feed slots in which a feed dog operates to feed the abutted edges of fabric sections, with stitch tongues located between the feed slots, and one in rear of the other, said stitch tongues being staggered relative to each other in the line of feed, whereby the cross threads laid across the rear stitch tongue will partially cover the cross threads laid across the forward stitch tongue.

A further object of the invention is to provide a throat plate having parallel spaced feed slots with two separate needle openings located between said feed slots and staggered relative to each other and relative to the direction of feed, said plate having stitch tongues projecting into the respective openings, across which tongues the cross threads of separate stitching mechanisms are respectively laid.

These and other objects will in part be obvious and will in part be hereinafter more fully disclosed.

In the drawings,—

Figure 1 is a plan view of a throat plate embodying my improvements;

Fig. 2 is a plan view of the front end of a work support showing a presser foot co-operating with my improved throat plate and also the position of the needles;

Fig. 3 is a plan view of the forward end of the work support with my improved throat plate attached; also showing the feed dog; 50

Fig. 4 is a detail partly in side elevation and partly in vertical section, showing the throat plate, the feed dog, the needles, the loopers co-operating therewith and the presser foot; 55

Fig. 5 is a perspective view of a slight modified form of throat plate;

Fig. 6 is a perspective view of the feed dog co-operating with the throat plate shown in Fig. 5; and 60

Fig. 7 is an enlarged detail, showing in bottom plan, two sections of fabric stitched on my improved throat plate.

I have shown my improved throat plate 1 as secured to the free end of a cylindrical work support 2. The throat plate is secured thereto by suitable screws 3—3. The throat plate is formed with parallel openings 6 and 7, which are spaced from each other and receive the outer webs of the feed dog 8. Said throat plate is also provided with openings 9 and 10 for other feeding webs on the feed dog. The throat plate is provided with an opening 11, and a stitch tongue 12 which is carried by the forward wall of the opening 65 and projects rearwardly into the opening. Said throat plate is also provided with a second opening 13 and a stitch tongue 14 which is carried by the forward wall of the said opening and projects rearwardly into the 70 same. 75

As clearly shown in Fig. 3, the needles 15 and 16 are spaced to enter the opening 11 in the throat plate at each side of the stitch tongue 12, while the needles 17 and 18 enter 85 the opening 13 at each side of the stitch tongue 14. Co-operating with the needles 15 and 16, beneath the work support, is a looper 19, while co-operating with the needles 17 and 18, beneath the work support, is a looper 90 20. A presser foot 21 operates to hold the material on the throat plate and this presser foot is provided with a needle opening 22 and a stitch tongue 23 for the rear pair of

needles 15 and 16, and there is an opening 24 and a stitch tongue 25 for the forward pair of needles 17 and 18.

In Fig. 7 of the drawings, I have shown 5 the lower face of a fabric stitched on my improved throat plate. The said fabric is formed with two sections f and f' which meet at f^2 . The fabric is fed in the direction of the arrow. The needles 17 and 18 10 form the needle loops a and b , respectively, while the needles 15 and 16 form the loops c and d , respectively. The looper 20 carries the looper thread e , while the looper 19 carries the looper thread g .

15 The looper thread e is laid across the stitch tongue 14, while the looper thread g is laid across the stitch tongue 12. The fabric sections are fed to the machine, so that the edges pass between the needles 15 and 20 18. The looper thread e is interlooped with the needle loops a and b , and as the looper threads slide off from the stitch tongue 14, they will pass over the throat plate in rear 25 of the opening 13 and may be drawn down flat against the fabric. The looper thread g is then laid across the rear stitch tongue 12 and overlaps and ties down a portion of the 30 cross threads connecting the needle loops a and b , as clearly shown in Fig. 7 of the drawings. In other words, by my improved 35 throat plate and arrangement of stitching mechanism, I am able to form complete stitches which join and cover the meeting edges of the fabric and subsequently form complete stitches which likewise join and 40 cover the meeting edges of the fabric and also overlap and tie down a portion of the first formed stitches.

In Fig. 5 of the drawings, I have shown 45 my improved throat plate 1 as having feed slots, 6, 7 and 9, and also as having an elongated opening 25'. The feed dog 8 is provided with a plate 26 which reciprocates in the opening 25'. This plate is formed with 50 needle openings 27 and 28, which are respectively similar to the openings 11 and 13, above described. These openings are respectively provided with stitch tongues 29 and 30, which are likewise similar to the 55 stitch tongues 12 and 14, above described. In other words, I have shown in Fig. 5 that I consider the placing of the stitch tongues on the feed dog the full equivalent of the placing of the stitch tongues on the throat plate, and although I have described and claimed specifically a throat plate construction, it is to be understood that the claims are intended to cover the placing of the stitch tongues on the feed dog as well.

50 From the above, it will be noted that the rear pair of needles are so disposed relative to the front pair of needles that one needle of each pair is located in a line parallel

with the line of feed and passing between the other pair of needles. It is this arrangement of the needles relative to each other that produces the overlapping cross threads of the stitching mechanisms in the finished seam. It will also be noted that the rear stitch tongue 12 is supported by the 65 throat plate which is in the form of a bar extending crosswise and separating the needle openings. This cross bar serves to insure the stitches as they pass off from the first stitch tongue passing upon to the throat 70 plate and over the top of the rear stitch tongue. 75

It is obvious that minor changes in the details of construction and arrangement of parts may be made without departing from 80 the spirit of the invention as set forth in the appended claims.

Having thus described my invention, what I claim as new and desire to secure by Letters Patent, is:

1. A throat plate having a feed slot and needle openings, said needle openings being staggered relative to each other in the direction of the line of feed, said throat plate having a stitch tongue extending into each needle opening, said stitch tongue in the rear needle opening having a portion thereof directly in rear of a portion of the stitch tongue in the front needle opening, the center line of the stitch tongue in the rear needle opening being at one side of the center line of the stitch tongue in the front needle opening, whereby the threads of the front stitching mechanism will be covered in part only by the threads of the 90 rear stitching mechanism. 95

2. A throat plate having parallel spaced feed slots and needle openings arranged between said feed slots, said needle openings being staggered relative to each other in the direction of the line of feed, said throat plate having a stitch tongue extending into each needle opening, the stitch tongue in the rear needle opening being disposed in a line parallel with the line of feed and located at one side of a line parallel with the line of feed passing through the other stitch tongue, whereby the threads of the front stitching mechanism will be covered in part by the threads of the rear stitching mechanism. 105 110 115

3. A throat plate having two separated needle openings, one in rear of the other, said openings being staggered relative to each other in the direction of the line of feed, and a stitch tongue extending rearwardly into each needle opening, the inner side edge of each stitch tongue being disposed in a line parallel with the line of feed and passing through the other stitch tongue. 120

4. The combination of a throat plate hav-

ing spaced feed slots, a feed dog coöperating with the throat plate, one of said elements having needle openings therein, a stitch tongue projecting into each needle opening, said needle openings being staggered relative to each other in the direction of the line of feed, whereby pairs of needles entering the respective needle openings may be disposed so that one needle of each pair

is located in a line parallel with the line of feed and passing between the other pair of needles.

In testimony whereof, I affix my signature, in the presence of two witnesses.

CHESTER McNEIL.
